G INVENTOR!
JOHN RIEPPEL,
BY H. W. Beadle & Co.
ATTYS:

UNITED STATES PATENT OFFICE.

JOHN RIEPPEL, OF RENOVO, PENNSYLVANIA.

DRILLING-MACHINE.

SPECIFICATION forming part of Letters Patent No. 280,956, dated July 10, 1883.

Application filed January 11, 1883. (No model.)

To all whom it may concern:

Be it known that I, JOHN RIEPPEL, of Reno-
vo, county of Clinton, and State of Pennsylva-
nia, have invented new and useful Improve-
ments in Drilling-Machines; and I do hereby
declare that the following is a full and exact
description of the same, reference being had
to the accompanying drawings, and to the let-
ters of reference marked thereon.

This invention is specially designed for drill-
ing boilers or other cylindrical objects from the
interior of the same; and it consists, broadly,
in the combination of a proper frame-work
having a journal at each end, and carrying an
actuating-shaft and proper drilling mech-
anism, with any proper bearing-support at one
end, and a central base-piece having radiating
supporting-arms with a capacity for radial ad-
justment at the other, as will be fully described
hereinafter.

In the drawings, Figure 1 represents a per-
spective view of my invention; and Fig. 2, a
detached view, showing the gearing, $f^2 g$, for
actuating the drill-shaft.

To enable others skilled in the art to make
my improved machine, I will proceed to de-
scribe fully its construction and manner of op-
eration.

A represents a three-branched base-piece,
having a hole or bearing for a journal-stud, b ,
held in the casting B, hereinafter referred to,
and three or more radiating arms, $a a a$, with
threaded ends, as shown.

$a' a' a'$ represent nuts upon the threaded ends
of the arms $a a a$, each of which is provided with
the conical projection a^2 , as shown.

B represents a casting, having a cap, b' , se-
cured thereto by bolts, which is provided with a
central hole adapted to hold the journal-stud
 b , as shown. A similar base-piece, A, with
arms, and casting B are located at the opposite
end of the machine, for furnishing the proper
support when the conditions of the case al-
lowed their use. If, however, from the short-
ness of the boiler or from other cause, the outer
supporting base-piece and arms cannot be used,
the casting B is secured to any proper cross-
bar, as shown in Fig. 1.

C C represent rods, secured at their ends to
the castings B B, these constituting a frame,
the rods of which are adapted to support the

cross-head E and the drilling mechanism, as
shown.

E represents a cross-head, which, by means
of side openings, is adapted to slide in a longi-
tudinal direction upon the frame-rods into any
desired position within the limits of the ma-
chine.

F represents the standard of the drill, sup-
ported by the cross-head; and f' , the drill-shaft, 60
having the bevel-gear wheel f^2 , Fig. 2, the
threaded portion f^3 , Fig. 1, the fixed wheel f^4 ,
and the tool-sockets $f^5 f^6$, one being located at
each end, as shown.

G represents the actuating-shaft, having at 65
one end the bevel-gear wheel g , adapted to en-
gage with the bevel-wheel of the drill-shaft, as
shown. g' represents a pulley, splined on the
shaft in such manner as to permit the latter
to move freely through the same as the position 70
of the drilling-machine is changed.

The operation is substantially as follows :
The machine having been located in the in-
terior of the boiler or other cylindrical object
to be drilled, the arms of the base-piece A are 75
adjusted in such manner as to cause the center
of the actuating-shaft to coincide exactly with
the center of the boiler. The cross-head then
may be adjusted upon the frame-rods to bring
the drilling mechanism into the proper posi- 80
tion longitudinally, and the drill itself, through
the medium of the revoluble frame, may be
swung into any desired position radially. The
machine then being set in motion, the drill may
be employed in the usual well-known manner. 85

Some of the advantages of the described con-
struction are as follows: By means of this ma-
chine the drilling necessary to be performed
inside of the boiler is done by power instead of
by hand. By means of the arms having a ca-
pacity for radial extension, it is possible to 90
center the axis of the revoluble frame with such
accuracy as to always obtain perfect uniformity
in the direction of the holes in the same hori-
zontal plane. The portions of the drill-shaft 95
upon each side of the center line vary in length,
and as each end has a tool-socket it follows that
the effect is the same as if the machine were pro-
vided either with a long or a short drill. It is
thus adapted for convenient use under varying 100
conditions.

I do not limit myself to the precise construc-

tion of frame-work shown, neither to the precise form of drill.

Having thus fully described my invention, what I claim as new, and desire to secure by 5 Letters Patent, is—

1. In combination with one or more supporting-pieces, A, having each a central journal-bearing, a revoluble frame-work, substantially as described, carrying an actuating-shaft and 10 proper drilling mechanism, as and for the purpose set forth.
2. In combination with the revolving frame-work, the drill-shaft having the single hand-wheel and fixed screw, and the two drill-sock- 15 ets, as shown.

3. The improved machine described, consisting of the base-piece A, having extensible radial arms and a central journal-bearing, the frame-work B.C, with journals, the cross-head E, the drilling mechanism Ff', and the actuating-shaft, combined and arranged as and for the purpose described. 20

This specification signed and witnessed this 4th day of January, 1883.

JOHN RIEPPEL.
